UNITED STATES PATENT OFFICE

FRANCIS R. UPTON, OF ORANGE, NEW JERSEY, AND FERNANDO J. DIBBLE,
OF PEABODY, MASSACHUSETTS.

PORTABLE ELECTRIC FIRE-ALARM.

SPECIFICATION forming part of Letters Patent No. 436,961, dated September 23, 1890.

Application filed March 24, 1890. Serial No. 345,104. (No model.)

To all whom it may concern:

Be it known that we, FRANCIS R. UPTON, of Orange, in the county of Essex and State of New Jersey, and FERNANDO J. DIBBLE, of 5 Peabody, in the county of Essex and State of Massachusetts, both citizens of the United States, have jointly invented an Improved Portable Electric Fire-Alarm, of which the following is a specification.

10 Our invention relates to devices for giving an audible local alarm when the temperature at a certain point rises above the predetermined limit.

15 Our object is to produce an alarm complete in itself, simple in construction, without complicated circuits, and which shall not require constant attention.

20 It is often found desirable to provide means for giving a local fire-alarm in buildings which are not wired and connected to the engine- 25 stations or fire-department of a city, as when a building is used temporarily for storage or like purposes, or in buildings outside of the fire-department limits. It may be desirable 30 also to use a local alarm, of the character hereinafter described, in buildings which are connected with the city fire-alarm system. In this case the local alarm might be so adjusted that it would be sounded before the 35 temperature should rise sufficiently high to operate the general alarm.

35 In the accompanying drawings, which illustrate our invention, Figure 1 is a side view of the device, showing the bell-dome in position in dotted lines and showing the shield for the 40 thermostatic device. Fig. 2 is a side elevation at right angles to that shown in Fig. 1, with the bell-dome and shield removed. Fig. 45 3 is a central section through Fig. 2, and Fig. 40 4 is a plan view of Fig. 2.

In general terms, the alarm may be said to consist in a battery with a bell, buzzer, or other sounder mounted thereon, a magnet in a normally-open circuit for operating said bell, and a thermostatic device, also on the 45 battery, for closing the normally-open circuit.

50 1 indicates the battery. 2 is the bell-dome thereon, and 3 the magnet for moving armature 4, which is shown suspended on pivot-screws bearing in the central post, and which

carries the bell-hammer. The battery is preferably provided with a central polar extension 5 and a peripheral polar extension 6. On the central pole is supported a metal or other plate 7, and upon this plate the magnet 55 above referred to is placed. Upon the same plate is the insulating-post 8, carrying an arm 9, which terminates in an adjustable electrical contact. From the center of plate 7 rises a post 10, preferably cut away for a portion 60 of its length and having a central bore, as shown. Through the upper part of this post extends an angle-rod 11, terminating in an electrical contact 12. The upper end of this angle-rod is rigidly connected to one end of 65 thermostatic coil 13, which is preferably composed of two metals of unequal expansibility, as is well understood. The other end of the coil is connected to a stationary part of the apparatus. Around this thermostatic coil we 70 may place a shield 14, composed of perforated sheet metal, wire fabric, or other suitable material, for protecting the coil from mechanical injury and at the same time improving the appearance of the complete apparatus. From 75 the other electrode 6 of the battery rises an arm 15, the end of which forms or carries an electrical contact, which in the normal condition of the apparatus is in contact with a co-operating terminal carried by spring 16, insulated from arm 15, as shown. This spring is weaker than the retracting-spring of the armature and is held compressed by means of said retracting-spring through the adjustable screw 17, which terminates in an insulating-point or is insulated from the frame of the apparatus. Spring 16 is connected by a wire 80 through the magnet to arm 9.

In using this alarm we adjust the contact in arm 9 to a certain distance from contact 90 12, the distance depending upon the degree of heat at which it is desired to sound the alarm. This adjustment can be made when the bell-dome is in position, since a screwdriver or other implement can be inserted 95 under the dome to reach the screw. The apparatus having been adjusted is placed in the room to be protected. As the temperature rises the thermostatic coil will be affected in such manner as to throw the angle- 100

lever and its contact 12 toward the contact in arm 9, and when the limit of temperature is reached for which the apparatus is adjusted said contacts will come together and will close the circuit as follows: Pole 5 of the battery, post 10, arm 11, contact 12, arm 9, through wire to magnet 3, to spring 16, arm 15, to the other pole 6 of the battery. This closure of the circuit energizes the magnet and attracts its armature, bringing the bell-hammer against the bell-dome. At the same time it raises the screw 17 from spring 16, allowing said spring to rise and break the circuit. As soon as this occurs the retracting-spring draws the armature back to its original position, thus again closing the circuit between 15 and 16, which again energizes the magnet. It will be seen that the contacts on 15 and 16 cause the bell to act as a vibrating bell in the well-known manner. Without this or some similar arrangement, the bell would give a single stroke only, and for that reason would not be very efficient in sounding an alarm; but with this arrangement the alarm continues to sound as long as the temperature remains high enough to keep the circuit closed between arms 9 and 11.

We prefer to use an ordinary dry pile or battery, since this is found to furnish sufficient current to require practically no attention and to last for a long period of time. Moreover, with this form of battery all danger of leakage of liquid or spilling the same by breakage of the jar is obviated; but evidently other forms of battery would serve the purpose.

By the construction which we have above described several important advantages are gained. In the first place, the thermostatic coil or device is raised away from the mass of the battery and other apparatus. It will therefore be much more sensitive to the influence of heat in the room where it is placed, since it will be affected at once and will not be dependent on the temperature of said mass. By placing the bell-dome as shown we thoroughly protect the circuit contacts and springs from mechanical injury and to a very large degree from dust, which otherwise would settle upon them. These parts are also hidden from sight by the dome.

Having thus described our invention, what we claim is—

1. The combination, in a portable fire-alarm,

of a battery, a plate on one pole supporting 55 a bell-magnet and an insulated circuit-terminal, a central post carrying the bell-dome, a thermostatic coil, said coil being connected to the contact co operating with the insulated circuit-terminal, and a terminal supported on 60 the second pole of the battery, substantially as described.

2. The combination, in a portable fire-alarm, of a battery, a post mounted on one pole thereof and supporting a thermostatic circuit controller and sounder, and an operating-magnet in circuit with said battery and circuit controller, substantially as described. 65

3. The combination, in a portable fire-alarm, of a battery, a post connected to one pole and 70 carrying a thermostatic device connected to an angle-lever, which constitutes a circuit-terminal, and co-operating contact connected through the operating-magnet to the second pole of the battery, substantially as described. 75

4. The combination, in a portable fire-alarm, of a battery, a post connected to one pole and carrying a thermostatic device which controls a circuit-terminal, and a co-operating terminal connected through the operating-magnet, 80 and a vibrator contact to the second pole of the battery, substantially as described.

5. The combination, in a portable fire-alarm, of a battery, a magnet, a thermostatic contact therefor connected to one pole of the battery, 85 a contact connected through the magnet to the second pole of the battery, and the bell-dome between the thermostatic device and the pole and covering said magnet and circuit contacts, substantially as described. 90

6. The combination, in a portable fire-alarm, of a battery, a bell and operating-magnet supported on said battery, a post carrying a thermostatic device above said bell and operating-magnet controlling the circuit of said 95 magnet, and an open-work shield for said thermostatic device, substantially as described.

This specification signed by said FRANCIS R. UPTON and said FERNANDO J. DIBBLE at 100 Harrison, New Jersey, the 17th day of March, 1890.

FRANCIS R. UPTON.
FERNANDO J. DIBBLE.
